CLAIM

The ornamental design for an archery quiver, as shown and described.

DESCRIPTION

FIG. 1 is a front and right side environmental perspective view of an archery quiver showing my new design;

FIG. 2 is a left side elevational view thereof;

FIG. 3 is a rear elevational view thereof, the front elevational view being a mirror image;

FIG. 4 is a right side elevational view thereof;

FIG. 5 is a bottom plan view thereof; and,

FIG. 6 is a top plan view thereof.

The broken line showing of an archer in FIG. 1 is for illustrative purposes only and forms no part of the claimed design. The carrying strap of the design is shown in an alternate position in FIG. 1.
